UNITED STATES PATENT OFFICE.

FRED EDWIN WOOD, OF SANGER, CALIFORNIA.

KIT FOR PLATE-HOLDERS.

1,297,957.

Specification of Letters Patent. Patented Mar. 18, 1919.

Application filed May 28, 1918. Serial No. 236,973.

To all whom it may concern:

Be it known that I, FRED E. WOOD, a citizen of the United States, and a resident of Sanger, in the county of Fresno and State 5 of California, have invented certain new and useful Improvements in Kits for Plate-Holders, of which the following is a specification.

My invention is an improvement in kits 10 for plate holders, and has for its object to provide a device of the character specified to be used in connection with the holder for permitting the holder to be used with plates of smaller sizes.

15 In the drawings:

Figure 1 is a perspective view of the improved kit.

Fig. 2 is a section on the line 2—2 of Fig. 1.

20 Fig. 3 is an end elevation of the slide end of the kit.

Fig. 4 is a top plan view of the end provided with the slide.

In the present embodiment of the invention, the improved kit consists of a frame 25 composed of side members 5 and end members 6 and 7, the said frame being of a size to fit within a plate holder. The end members 6 and 7 of the kit frame have at their 30 under faces tongues 9 which are adapted to engage in undercut portions in the plate holder frame.

The end member 7 of the kit frame is a plate of sheet metal, which is at that face 35 of the kit that will be adjacent to the central partition of the holder. At the opposite end a plate 10 is secured to the same face of the kit, and the end member 6 is beveled on that edge adjacent to the opening of the frame. Both the end member 6 at its inner edge and the plate 10 have rounded notches or recesses 11 to permit the insertion of the finger or thumb to remove the kit. A slide 12 is arranged at the end

of the frame adjacent to the plate 7, the 45 said slide being movable on the plate 7 within limits.

Corner pieces 13 are secured to the kit frame on the opposite face from the plate 7, the said corner pieces being countersunk, 50 and a pin 14 extends from each corner piece to the plate 7. These pins pass through transverse slots 15 in the slide 12, providing thus a slidable connection for the slide with the frame. 55

In use, the kit is inserted in the plate holder by placing that end provided with the slide against the spring pressed piece carried by plate holders. The kit frame is pressed toward this movable piece and at 60 the same time pushed into the plate holder frame. It will be noticed that the inner edge of the slide 12 is beveled, and to insert the dry plate one end thereof is placed against the slide beneath the bevel, and 65 the plate is pushed longitudinally until the other end will slip beneath the bevel of the end piece 6, the said piece being also beveled on its inner edge.

It will be evident that the kits may be 70 made of dimensions to suit any size of plate holder and they may be of any width to provide for various sizes of plates. With several kits of different dimensions a single plate holder may be utilized for plates of any size 75 smaller than those for which the plate holder is intended.

I claim:—

A kit for plate holders comprising a frame having one end thereof slidably connected 80 with the body of the frame to be pressed toward the other end, said slidably end and the other end of the kit frame having their inner edges beveled to engage over the plates.

FRED EDWIN WOOD.
